UNITED STATES PATENT OFFICE.

JEREMIAH HORAN, OF NEW YORK, N. Y.

BOOK CONTAINER FOR PACKAGED FOODSTUFFS.

Application filed December 2, 1921. Serial No. 519,337.

To all whom it may concern:

Be it known that I, JEREMIAH HORAN, citizen of the United States, residing at New York, in the county of New York and

5 State of New York, have invented certain new and useful Improvements in Book Containers for Packaged Foodstuffs, of which the following is a specification.

This invention relates to a container for 10 packaged foodstuffs, such as cereals, having more particular reference to a container of book-like form in which cartons of various sizes can be readily fitted, in a manner for convenient discharge of the material 15 therein, the present invention being an improvement over one disclosed in a previous patent application filed by me on July 21, 1921, under Serial Number 486,456.

The present invention has for an object 20 to generally improve the container, and more specifically to provide improved means for holding different sized cartons in proper relation to the mouth of the container, and for operating the door closing the mouth of 25 the container.

For further comprehension of the invention, and of the objects and advantages thereof, reference will be had to the following description and accompanying drawings, and to the appended claims in which the various novel features of the invention are more particularly set forth.

Fig. 1 of the drawings is a perspective view of my improved book-shaped container.

35 Fig. 2 is a longitudinal vertical sectional view thereof, this view being taken along the line 2—2 of Fig. 3.

Fig. 3 is a transverse vertical section of 40 the container taken along the line 3—3 of Fig. 2.

Fig. 4 is a horizontal sectional view taken along the line 4—4 of Fig. 2.

45 Fig. 5 is an enlarged fragmentary vertical section, taken on the line 5—5 of Fig. 4 and illustrating particularly the means for holding the movable wall member in adjusted positions.

50 Fig. 6 is a fragmentary transverse sectional view illustrating a modified arrangement of the door operating means.

Fig. 7 is a fragmentary central longitudinal section of the parts shown in Fig. 6.

55 As here shown my improved container is shaped, and has an exterior appearance, corresponding to a book, the side walls of

the container being indicated at 10, and the top and bottom walls at 11 and 12 respectively. The container has a fixed rear end wall 13 and a movable front end wall 14, 60 to which latter further reference will be presently made. The side walls 10 project vertically beyond the top wall 11, preserving the book-like form and also acting as a shield for the door operating means. The 65 end wall 13 is rounded as shown, and may be formed with ribs 15 such as are common on leather bound books, while the side walls 10 may have triangular projections 16 such as are found in books.

Just inside the curved rear wall 13 is a straight transverse partition 18 against which the carton abuts, a full carton being shown at 19 in position in the container, the carton having one edge cut off to provide 70 an opening 20 through which the food is removed.

To provide for discharge of the material from the container the latter is provided at its upper rear edge with an inclined, or 80 diagonal, discharge opening with which the opening in the carton registers when the latter is in position in the container. The opening in the container is closed by a cap 22 which is of triangular form as seen in 85 side view, being shaped to preserve the book-like appearance of the container.

This cap 22 is fixed at one edge to a pintle 23 extending transversely of the top 11, on which it is rotatably mounted. The 90 pintle 23 has a crank element 24 formed midway of its ends which is engaged by the rear end of a bar 25 slidable longitudinally on the container top 11 and provided at its forward end with an upstanding thumb-piece 26. This bar 25 is adapted to open the cap 22 against the tension of springs 27 surrounding the pintle 23 and urging the cap to closed position. To provide for holding the cap 22 in opened position the 100 front end of bar 25 is widened and formed with a longitudinal slot 28 having its rear end laterally offset as at 29. A headed stud 30 is fixed in the container top 11 and projects freely through the slot 28, serving the 105 double purpose of guiding the bar 25 and holding the cap open by engaging in the offset 29.

The partition 18 is bent rearwardly at the top thereof in a spout-like form as at 18' 110 to join the rear end wall 13, while the cap 22 has its interior closed by an inside wall

32 whose rear end is formed complementary to the spout-element 18'.

In order to enable cartons of smaller size than the container to be fitted into the latter with their discharge openings held in registry with the mouth of the container, the front end wall 14 is in the form of a plate adjustable toward and away from the rear end wall 13. Projecting inwardly from this plate 14 are a pair of sharp spikes 35 which engage in the carton 19 and hold the latter raised above the bottom of the container when the size of the carton renders this necessary. If desired these spikes 35 may be mounted on the partition 18 instead of the plate 14 if so desired.

To hold the plate 14 in proper adjusted position a pair of rack-elements 36 extend along the top and bottom walls of the container and are adapted to be engaged by bolts 37 vertically slidable in housings 38 fixed to the upper and lower ends of plate 14. Each bolt 37 is normally urged to released position by means of a coiled expansion spring 39 surrounding the same in the housing 38 and bearing upwardly against a collar 40 fixed to the bolt. This collar 40 has a rigid depending ratchet finger 41 which is engaged by pin 42 transversely slidable in the housing 38 to hold the bolt 37 engaged with the rack 36. The pin 42 is normally urged to position engaging the ratchet finger 41 by a coiled expansion spring 43 surrounding the same in a housing and bearing on a collar 44 fixed to the pin. The pin 42 and bolt 37 have projecting heads 42' and 37'.

The plate 14 preferably has a movable hinge connection with the bottom 12 of the container, permitting it to be swung out of the container, for insertion of a new carton therein, without being entirely detached from the container. As here shown the bottom rack 36 is raised above the bottom of the container, leaving a longitudinal slot 45 under said rack, through which is passed a bail-like rod 46 fastened at its ends to the plate 14.

To provide for the proper centering of cartons of less width than the container a pair of flat springs 48 are fixed at their front ends to the side walls 10, just under the top 11, and have their rear ends sprung in toward one another as shown in Fig. 4, these rear ends being moved out against the side walls when full width cartons are inserted in the container.

It is believed that the manner of use of my improved container will be readily understood from the above description. When a new carton is to be inserted, the pins 42 are pulled, releasing bolts 37 which are thrown back by the springs 39. The plate 14 may then be swung back and a new carton inserted, the plate being then moved into

contact with the carton and the bolts 37 re-engaged with the racks 36 by pressing on their heads 37'. To aid in removing the empty carton from the container a flat spring 49 may be fixed to the rear face of partition 18 and may have a bowed end projected through a slot 18' in the said partition.

In Figs. 6 and 7 of the drawings I have shown a modified arrangement of the door or cap operating means in which the cap is fixed to a pintle 23' carried under the top 11 and having a crank element 24' engaged by a bar 25' slidable under the top 11 and having a thumb-piece 26' extending up through a slot 50 in the top 11, it being understood that this slot will have a lateral offset in its front end similar to the offset in slot 28. In Fig. 6 I have shown the side walls 10 as provided with inwardly projecting top flanges 10' which enable the containers to be piled one on top of the other if desired.

Although it is generally desirable to retain the packaged material in its original carton when placed in the container it is understood that a metal container especially constructed to fit container 10 may replace carton 19 if so desired.

Having thus described my invention what I claim as new and desire to protect by Letters Patent of the United States is as follows:

1. In a container for packaged foodstuffs, a movable wall element, a pair of rack members at opposite ends thereof, and bolts carried by said movable wall element, and engaging said racks, springs normally urging said bolts to released position, ratchet fingers fixed to said bolts, and spring pressed pins engaging said ratchet fingers to hold said bolts in locking position.

2. A container having a discharge opening, a cap closing said opening, a hinge pintle to which said cap is attached, a crank-element on said hinge pintle, a slide-bar connected at one end to said crank element, said slide-bar having its opposite end formed with a longitudinal offset at one end, and a headed stud projecting through said slot.

3. A container for packaged foodstuffs comprising a casing of book-like form having a discharge opening at one corner thereof, the rear end wall of said casing being fixed and of rounded cross section, the front end wall being in the form of a movable plate, and a transverse partition in said casing a short distance in front of said rear wall and having its upper end curved backward in spout-like form to meet said rear end wall at the edge of the said discharge opening.

4. A container for packaged foodstuffs comprising a casing of book-like form having a discharge opening at one corner thereof, one wall of said casing being in the form

of a movable plate, and a spring carried by the opposite wall and having a portion projected normally into the body of the container toward the said movable wall.

5 5. A container for packaged foodstuffs comprising a casing having a discharge opening at one corner thereof, one of the walls opposite the said corner being in the form of a movable plate, a transverse par-

10 tition in said casing a short distance from

the wall opposite to the movable plate, said partition having an opening therein, and a spring fixed at one end to said partition and having its opposite end normally projecting through said opening toward the said movable plate. 15

In testimony whereof I have affixed my signature.

JEREMIAH HORAN.
